(57) **CLAIM**

The ornamental design for a multi-component golf club head, as shown and described.

DESCRIPTION

FIG. 1 is a top perspective view of a multi-component golf club head;

FIG. 2 is a bottom perspective view of the golf club head of FIG. 1;

FIG. 3 is a top view of the golf club head of FIG. 1;

FIG. 4 is a bottom view of the golf club head of FIG. 1;

FIG. 5 is a front view of the golf club head of FIG. 1;

FIG. 6 is a rear view of the golf club head of FIG. 1;

FIG. 7 is a heel side view of the golf club head of FIG. 1;

FIG. 8 is a toe side view of the golf club head of FIG. 1;

FIG. 9 is a top perspective view of the body portion of the multi-component golf club head, shown for clarity of illustration;

FIG. 10 is a bottom perspective view of the golf club head body of FIG. 9;

FIG. 11 is a top view of the golf club head body of FIG. 9;

FIG. 12 is a bottom view of the golf club head body of FIG. 9;

FIG. 13 is a front view of the golf club head body of FIG. 9;

FIG. 14 is a rear view of the golf club head body of FIG. 9;

FIG. 15 is a heel side view of the golf club head body of FIG. 9;

FIG. 16 is a toe side view of the golf club head body of FIG. 9;

FIG. 17 is a top perspective view of the crown insert of the multi-component golf club head, shown for clarity of illustration;

FIG. 18 is a bottom perspective view of the crown insert of FIG. 17;

FIG. 19 is a top view of the crown insert of FIG. 17;

FIG. 20 is a bottom view of the crown insert of FIG. 17;

FIG. 21 is a front view of the crown insert of FIG. 17;

FIG. 22 is a rear view of the crown insert of FIG. 17;

FIG. 23 is a heel side view of the crown insert of FIG. 17; and,

FIG. 24 is a toe side view of the crown insert of FIG. 17. The broken lines shown form no part of the claimed design.

1 Claim, 19 Drawing Sheets
